CLAIM

The ornamental design for a ceiling fan blade, as shown and described.

DESCRIPTION

FIG. 1 is a bottom front perspective view of a novel ceiling fan blade.

FIG. 2 is a top front perspective view of the blade of FIG. 1.

FIG. 3 is a bottom view of the blade of FIG. 1.

FIG. 4 is a top view of the blade of FIG. 1.

FIG. 5 is a right side view of the blade of FIG. 1.

FIG. 6 is a left side view of the blade of FIG. 1.

FIG. 7 is a front end view of the blade of FIG. 1; and,

FIG. 8 is a rear end view of the blade of FIG. 1.

The broken line showing of the holes is included for the purpose of illustrating environmental structure and forms no part of the claimed design.

1 Claim, 6 Drawing Sheets
